INVENTOR.

BY
Thomas R. Harvey ATTORNEY.

UNITED STATES PATENT OFFICE.

ELWIN HARRIS BERG, OF EVELETH, MINNESOTA.

WEATHER-STRIPPING.

1,400,206.

Specification of Letters Patent. Patented Dec. 13, 1921.

Application filed December 3, 1920. Serial No. 428,029.

To all whom it may concern:

Be it known that I, ELWIN H. BERG, a citizen of the United States of America, residing at Eveleth, in the county of Saint Louis and State of Minnesota, have invented certain new useful Improvements in Weather-Stripping, of which the following is a specification.

My present invention relates generally to window stripping, and more particularly to metal weather stripping which though especially applicable to the sides of sliding sashes, may be utilized in connection with swinging sashes, doors and the like, as for instance at the top and latch sides thereof, and is simple in construction, effective in use and easily applied and maintained in proper position.

In the accompanying drawing which illustrates my present invention and forms a part of this specification,

Figure 1 is a horizontal section through one side of a window frame and the adjacent sides of upper and lower sashes, illustrating the application of the preferred form of my invention,

Fig. 2 is a detail transverse section through the weather strip proposed by my invention,

Fig. 3 is a partial side view thereof, and Fig. 4 is a transverse section through a slightly modified form of construction.

Referring now to these figures, I have shown in Fig. 1 a conventional window frame including a jamb 10 in which a parting strip 11 is as usual partly set and located between an outer blind stop 12 and an inner sash stop 13, the jamb 10 being for the purposes of my invention provided with grooves 14 and 15 respectively along the inner edges of the blind stop 12 and the parting strip 11 for a purpose which will be presently described.

The upper and lower sashes 16 and 17 slide respectively within the spaces between the blind stop 12 and parting strip 11 and the parting strip 11 and the inner stop 13, and against the inner face of the jamb 10 and within each of these spaces the weather strip proposed by my invention is seated and connected to the jamb.

As shown in Figs. 2 and 3 the weather strip comprises a transversely curved body 18, or at least a body which is transversely curved for a portion of its width, the body 18 in Fig. 2 being shown with substantially flat side portions 19, one of which has a con-

tinuation bent at approximately right angles thereto and doubled to form a tongue 20 adapted to enter one of the jamb slots 14, 15. One side of this doubled portion forming tongue 20 is extended beyond the relatively opposite side of the body 18 and is bent and doubled to form a second tongue 21 at right angles to the tongue 20 and in parallel spaced relation to the body, so as to enter a slot 22 formed in the outer face of each of the sashes 16 and 17.

In addition to supporting the tongues 20 and 21, the extension at one side of the body 18, standing at approximately right angles thereto, forms an abutting member which, placed adjacent to the inner sash 17, engages the adjacent face of the parting strip 11, and when placed adjacent to the outer sash 16 engages the adjacent face of the blind stop 12.

In order that the body 18 may still be free to flex in a direction at right angles to its plane, in spite of the abutment of its angular portion against a rigid portion of the window casing as just above described, the relatively opposite side of the body 18 is preferably provided with transversely elongated slots 23, one of which is shown in Fig. 3, to receive fastening members 24 in such a way that the body while held to the jamb by fastening members 24 is still permitted slight play in respect to the fastening members.

It will be noted from a careful inspection of Fig. 2 that the tongue 20 projecting beyond one face of the body 18 is short as compared to the angular extension carrying the tongue 21, and it becomes obvious therefore that by first bending the metal to form the tongue 20 and then extending one side of this tongue to carry the tongue 21, I save a portion of metal as compared to the construction shown in Fig. 4 wherein the body 18^a is bent angularly in the first instance to form the sash engaging tongue 21^a and then continued in the opposite direction to form the jamb entering tongue 20^a.

For the above reasons, and while my invention is capable of modification in its specific construction along the last described, and possibly other lines, the first construction disclosed is at the present time to be preferred in view of the strict economy in metal.

According to either construction it is obvious the weather strip will effectively and efficiently operate to the end desired in the

use thereof, and may be readily and quickly applied.

According to Fig. 1 furthermore the sashes 16 and 17 have the usual weight cord 5 grooves 16^a and 17^a shown in dotted lines, and in order that the curved body portion 18 of the weather strip may readily extend into and engage the side edges of these grooves, the sash sides may have slots 16^b and 17^b extending 10 throughout the length of each sash stile, which slots open into the sash cord grooves so that throughout the entire height of each sash in its normal position the body portion of the weather strip will have a two point bearing.

By thus having the weather strip secured at one side of its body in yielding relation to the jamb and slidably engaged at its opposite side with the window sash against 20 lateral displacement relative to the sash, it is also obvious that in case of shrinking of the sash away from the jamb, the sash engaged edge of the weather strip will follow the sash and will be maintained in effective 25 relation between the parts at all times. It is further obvious that by the extension of the tongue of the weather strip slidably into the groove of the sash, my improved weather strip will operate effectively in connection 30 with sashes including not only those which are straight but also those which have warped.

I claim:

1. The combination with a window jamb 35 and sash, of a metal weather stripping consisting of a body portion having a hump engaging the side of the sash and provided with jamb connecting means at one side of the hump, and means at the opposite free side 40 of the hump having sliding engagement with

one face of the sash whereby to shift the body portion with the sash when the latter shrinks from the jamb and thus maintain uniform contact between the hump of the body and the side of the sash, said sash having along its side a vertical slot forming relatively sharp edges along its opposite sides engaged by the hump of the body at opposite sides of its center. 45

2. A metal weather strip comprising a 50 transversely curved body having transversely elongated slots adjacent to one side and having a doubled laterally extending rib at right angles to its opposite side projecting beyond one face of the body, one wall of said 55 rib having an extension projecting at right angles to the body and beyond its opposite face for a distance greater than the width of the said rib, said extension having a tongue projecting parallel to the body portion and in spaced relation to the said body portion 60 as described.

3. The combination with a window jamb and sash, the later having a lengthwise slot 65 in line with the usual weight cord groove, the said sash also having a groove in its front face paralleling its side edge, of a weather strip having a curved body portion between the sash and jamb to engage the edges of the sash at opposite sides of the 70 said slot and the usual weight cord groove, said body of said strip being connected at one side of the jamb and having its opposite free side provided with an angular portion projecting in front of the sash having a 75 tongue slidably disposed within the front groove of the sash as described.

In testimony whereof I have affixed my signature.

ELWIN HARRIS BERG.
